UNITED STATES PATENT OFFICE.

WILLIAM B. SPERMAN, OF MOUNDS, OKLAHOMA.

COMMUTATOR.

1,414,313.

Specification of Letters Patent. Patented Apr. 25, 1922.

Application filed November 2, 1918, Serial No. 260,882. Renewed September 19, 1921. Serial No. 501,826.

To all whom it may concern:

Be it known that I, WILLIAM B. SPERMAN, a citizen of the United States, residing at Mounds, in the county of Creek and State of Oklahoma, have invented certain new and useful Improvements in Commutators; and I do hereby declare the following to be a full, clear, and exact description of the invention, such as will enable others skilled in the art to which it appertains to make and use the same.

This invention relates to improvements in commutators for internal combustion engines of automobiles and has for one of its objects the provision of means whereby the circuit through the commutator can be broken so as to prevent the starting of the engine, thus locking the automobile against theft.

Another object of this invention is the provision of the contacts movably mounted in the shell or casing and having means connected thereto for moving them into and out of engagement with the contact poles, when desired, and which means is controlled by a key whereby an unauthorized person is prevented from starting the engine.

A further object of this invention is the provision of means on the contact roller for preventing the same from being used in conjunction with an ordinary commutator shell or casing, thus obviating an unauthorized person from removing the shell or casing and substituting an ordinary one therefor.

A still further object of this invention is the provision of a commutator of the above stated character, which shall be simple, durable, and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my

invention, reference is to be had to the following description and accompanying drawing, in which:-

Figure 1 is a rear elevation partly in section of the commutator constructed in accordance with my invention, 55

Figure 2 is a vertical sectional view of the same, and

Figure 3 is a fragmentary sectional view illustrating the contacts. 60

Referring in detail to the drawing, the numeral 1 indicates the casing or shell of a commutator, which is adapted to be secured to an internal combustion engine in the usual manner and has formed thereon the ordinary ear 2 provided with an aperture 3' for receiving a spark controlling rod or element. A stationary ring 3 is secured within the casing or shell 1 and is constructed of fiber or any other non-conducting material, and is provided with relatively spaced openings to receive contact poles 4 that extend through openings in the casing or shell 1 for connection with the feed wires that lead to the coils of an automobile. A movable ring 5 is rotatably secured within the stationary ring 3 and is constructed of fiber or any other non-conducting material, and is provided with relatively spaced openings to receive contacts 6 that are adapted to engage at their outer ends with the inner ends of the contact poles 4, under ordinary running conditions of the engine. A sleeve 7 is secured to the timing shaft 8 of the engine in the ordinary manner and has formed thereon relatively spaced ears 9 between which is pivoted a contact arm 10, having one end secured to the sleeve 7 by means of a coil spring 11, while its opposite end has journalled 90 thereto a contact roller 12.

An extension 13 is formed upon the contact arm 10 and is adapted to limit the outward movement of the contact roller 12 for the purpose of preventing the same from being used in conjunction with an ordinary commutator shell or casing. If an ordinary commutator shell or casing is applied or substituted for the shell 1 of this invention, the distance between the contacts thereof 100

and the hub 7 is too great for the roller 12 to engage said contacts and to prevent any possibility of the roller 12 engaging said contacts, the lug or stop 13 is provided.

5 The casing or shell 1 is provided with an opening in which is rotatably secured a plug 14 having secured to its inner end a gear 15 adapted to mesh with teeth 16 formed upon the movable ring 5 and which are located between a pair of the contacts 6, whereby upon rotating the plug 14 the contacts 6 may be moved into or out of engagement with the contact poles 4. The plug 14 is provided with a key opening to 15 receive a key 17 so that said plug can be readily turned in either direction for moving the contacts 6 into and out of engagement with the contact poles 4.

In use, the contacts 6 are disposed in engagement with the contact poles 4 and the contact roller 12 rotates against the inner wall of the movable ring 5 and when the same engages the contacts 6 electric circuits are completed to the various cylinders of the 25 engine. When it is desired to lock the engine, the key 17 is inserted within the key hole in the plug 14 so as to turn said plug moving the ring 5 in a position to disconnect the contacts 6 from the contact poles 4, thus preventing an electric circuit being completed to the cylinders of the engine.

The keyhole of the plug 14 is made in a peculiar shape and the key shaped accordingly, so that a certain key must be used 35 before the device can be locked or unlocked.

While I have shown and described the preferred embodiment of my invention, it will be understood that minor changes in construction, combination, and arrangement 40 of parts may be made without departing from the spirit and scope of the invention as claimed.

Having thus described my invention, what I claim is:—

45 1. A commutator comprising a shell, a non-conductive ring secured within said shell and having openings, poles carried by said shell and extending through said openings, a movable ring constructed of non-conducting material rotatably mounted within the first named ring and having spaced 50 openings, contacts located within the openings of the movable ring, teeth formed upon the movable ring between a pair of the contacts, a contact roller disposed within the movable ring and adapted to be rotated by the engine to consecutively engage the contacts, a plug journaled in the casing and having a keyhole, a gear secured to said plug 55 and in mesh with the teeth and a key adapted to fit the keyhole for rotating the plug.

2. A commutator including means adapted for adjustment to establish an electrical connection between the contact and binding 60 posts of the commutator and for adjust-

ment to break said connection, and means for locking said first means in adjusted position.

3. A commutator including means forming a part thereof and adapted for adjustment to 70 establish an electrical connection between the contact and binding posts of the commutator and for adjustment to break said connection, and means for locking said first means in adjusted position.

4. A commutator including means located between the binding post and contact of the commutator and adapted for adjustment to 80 establish an electrical connection between the contact and binding posts of the commutator and for adjustment to break said connection, and means for locking said first means in adjusted position.

5. A commutator including means adapted for adjustment to establish an electrical 85 connection between the contact and binding posts of the commutator and for adjustment to break said connection, and means carried by the commutator for locking said first means in adjusted position.

6. A commutator including means adapted for adjustment to establish an electrical connection between the contact and binding posts of the commutator and for adjustment to break said connection, and means 90 for moving and locking said first means in adjusted position.

7. A commutator including an element carrying binding posts and a movable contact, means engaged by the contact and adjustable relative to said element and adapted when in one position to engage the posts to render the device operative and when in another position to disengage the posts to render the device inoperative, and means 100 for locking said first means against movement relative to said element.

8. A commutator including an element carrying binding posts and a movable contact, means engaged by the contact and adjustable relative to said element and adapted when in one position to engage the posts to render the device operative and when in another position to disengage the posts to render the device inoperative, and means 110 carried by said element for moving the second means relative to said element and to lock said second means in either of its positions.

9. A commutator including a movable contact, an element carrying binding posts, a second element carrying conductors establishing electrical connection between said contact and binding posts, said elements being capable of relative adjustment to break 120 said connection, and means for locking said parts in such adjustment.

10. A commutator including parts adapted to be adjusted relatively to each other and the contact of the commutator to render 130

the commutator inoperative, and means for locking said parts in such adjustment.

11. A commutator including sectional electric conductors, a contact, and means by 5 which the sections of the conductors may be adjusted relatively and locked to render the commutator inoperative.

12. A commutator including a rotating contact and a series of conductors arranged 10 about said contact, each of said conductors

consisting of sections adapted for adjustment relatively to lock the commutator in its inoperative position.

In testimony whereof I affix my signature in presence of two witnesses.

W. B. SPERMAN.
